SOLON J. BOUGHTON, OF TOLEDO, OHIO, ASSIGNOR TO THE WILLYS-OVERLAND COMPANY, OF TOLEDO, OHIO, A CORPORATION OF OHIO

ENGINE-LUBRICATION SYSTEM

Application filed February 23, 1927. Serial No. 170,200.

This invention relates to internal combustion engines, and more particularly to lubrication of internal combustion engines of the sleeve valve type.

One of the objects of the invention is to provide a sleeve valve engine, in which the sleeve lubricant is prevented from entering the combustion chamber of the engine.

Another object of the invention is to provide a sleeve valve engine with a means for removing excessive amounts of lubricant from the sleeves, and returning it to the crankcase.

Another object of the invention is to provide a valve sleeve for an internal combustion engine that may be used as a fluid pump.

Another object of the invention is to provide a sleeve valve engine, in which the movement of the sleeves is utilized for controlling the oil supply.

Other objects will appear from the description to follow, in conjunction with which, for the purposes of the present application I have illustrated one embodiment of the invention in the accompanying drawings which may be preferred, in which:

Figure I is a front elevation, partly in section, of a portion of a sleeve valve engine embodying the invention.

Fig. II is a view similar to Fig. I in which the outer sleeve is shown in its highest position.

Fig. III shows the engine with the outer sleeve in the lowest position.

Fig. IV is a detail of the inner sleeve.

Fig. V is a detail of the outer sleeve.

Fig. VI is a detail of the piston.

Referring to the drawings in which like characters refer to like parts, through the views, 1 is a cylinder of an internal combustion engine, in which reciprocates piston 2. Interposed between piston 2 and cylinder 1 are inner valve sleeve 3 and outer valve sleeve 4, which are provided with inlet ports 5 and 6 respectively, each having exhaust ports 7 and 8 respectively, and a junk ring 9 positioned within the cylinder and operatively disposed with respect to the sleeves. Both sleeves are reciprocated by an engine driven eccentric shaft 10 through connecting rods 11

and 12, the sleeves having their respective eccentricities displaced slightly with respect to each other, in order to move the sleeves relative to each other as well as cylinder 1. Sleeve valve engines, similar to the one described, are well known in the art, and create lubrication problems that are not present in the poppet valve type. The engine suction present in cylinder 1 during the intake stroke of piston 2, causes oil which ordinarily exists as an oil mist in crank case 13, to be drawn up between the sleeves 3 and 4 and between the outer sleeve 4 and cylinder 1, into the combustion chamber 14 of the engine. It is desirable to check this oil flow before it reaches inlet ports 5 and 6, and to secure this result I propose using the outer sleeve as an oil pump. Cylinder 1 has its outer end enlarged at 16 to provide a pump cylinder, the preferred form being a counterbore concentric with the main bore, but if desired any other form of recess may be used. Outer sleeve 4 has an enlarged collar portion 17 which fits within counterbore 16 in lapped relation thereto, and is provided with compression rings 18. The reciprocation of the sleeve causes the annular space 20 above collar 17 to vary in volume, and act as a lubricant pump. An oil inlet from the outer sleeve surface is provided by forming a groove 22 therein which preferably communicates with a cross groove 23 extending circumferentially of sleeve 4 beneath inlet ports 6. Groove 22 is continued downwardly to approximately the shoulder 24 of collar 17, so that it is at all times in communication with space 20.

An opening 25 is provided in sleeve 4, adjacent shoulder 24 which forms the outlet to the pump space 20. Inner sleeve 3 is provided with an opening 26 which periodically registers with opening 25 for controlling the oil discharge. It may be noted that the skirt 27 of piston 2 covers opening 26, and to guard against piston 2 obstructing the free flow of oil from the sleeve outlet, I prefer to locate the usual piston slots 28 and 30 in line with or adjacent to the inner sleeve opening 26. Inner sleeve 3 is also provided with a short vertical groove 31 which causes the registration of openings 25 and 26 to be effective over

a greater period of time, and a cross groove 32 beneath inlet ports 5 which communicates with outer sleeve groove 22 by means of vertical groove 33 and an opening 34 through the wall of outer sleeve 4. The usual oil distribution grooves 35 may be used on those portions of the sleeve surface that will not register with the before-mentioned passages and openings.

10 In the operation of the engine, inner sleeve 3 reciprocates slightly in advance of the outer sleeve 4 as may be seen in the diagrammatic showing of the sleeve eccentrics in Figs. II and III. From the position shown in Fig. II both sleeves are moving downwardly, opening 25 is sealed by the body portion of sleeve 3, and any oil which may have collected on the outer sleeve surface is drawn downwardly from grooves 23 and 22 into the annular space 20. Moreover, oil from the surface of the inner sleeve is drawn from grooves 32 and 33 through opening 34 into the outer sleeve groove 22, and into the space 20.

Outer sleeve 4 descends to the position shown in Fig. III at which position the inner sleeve 3 has moved upwardly and groove 31 has uncovered the pump outlet opening 25. From the position shown in Fig. III outer sleeve 4 moves upwardly, and oil is forced out of space 20 through outer sleeve opening 25 and inner sleeve opening 26 onto piston 2. In the position shown in Fig. III piston 3 has that portion immediately below the head 36 covering the inner sleeve opening 26, but piston 35 tons are ordinarily reduced in size at this point and shortly thereafter the more rapidly moving piston has reached a position where slots 30 and 28 register with opening 26 and the oil may freely discharge into the 40 crankcase 13. Groove 22 is at all times in communication with the pump space 20, but the openings 25 and 26 are larger, and the major portion of the oil is discharged through the more direct passageway formed by the larger openings, in preference to the more tortuous, smaller passageways forming the pump inlet. The upward motion of both sleeves continues until substantially the position shown in Fig. I, at which position inner 50 sleeve 3 is descending, but the outlet 25 is still open because of groove 31. This outlet remains open until substantially the uppermost position of outer sleeve 4 as shown in Fig. II, and the suction stroke is resumed as before.

It may readily be seen from the foregoing description that I have provided a sleeve valve engine, with an integral pump which acts to draw excessive lubricant from beneath the inlet ports, and which prevents the oil on the sleeve surfaces from entering the combustion chamber to the detriment of the proper working of the engine.

While I have illustrated and described, somewhat in detail, one embodiment of my

invention, it is to be understood that this showing and description are illustrative only, and that I do not regard my invention as limited to the details of construction illustrated and described, except in so far as I have included such limitations within the terms of the following claims, in which it is my intention to claim all novelty inherent in the invention, broadly as well as specifically.

I claim:

1. In an internal combustion engine, the combination of a cylinder, a reciprocating valve sleeve therein, said cylinder having a recess therein, said valve sleeve having an enlarged portion in lapped relation to the walls of said recess, means forming a passageway on said sleeve communicating with said recess for permitting ingress of fluids from the sleeve surface into said recess, means forming an outlet passageway from said recess, and valving means for one of said passageways.

2. In an internal combustion engine, the combination of a cylinder having a bore and counterbore, a reciprocating sleeve within said bore having an enlarged cylindrical portion in lapped relation to the walls of said counterbore, means forming a passageway on said sleeve communicating with said counterbore for permitting ingress of fluids from the surface of said sleeve into said recess thereto, means forming an outlet passageway from said counterbore, and valving means for one of said passageways.

3. In an internal combustion engine, the combination of a cylinder having a recess therein, a reciprocating sleeve within said cylinder having an enlarged portion in lapped relation to the walls of said recess, means forming a passageway on said sleeve communicating with said recess for permitting ingress of fluids from the surface of said sleeve into said recess, means forming an outlet passage from said recess, and valving means for said outlet passage.

4. In an internal combustion engine, the combination of a cylinder having a recess therein, a pair of concentric reciprocating valve sleeves within said cylinder, the outer of said sleeves having an enlarged portion thereon in lapped relation to the walls of said recess, means forming a passageway on said outer sleeve communicating with said recess, said outer sleeve having an opening therethrough forming an outlet from said recess, and said inner sleeve acting as a valve to open and close said outlet.

5. In an internal combustion engine, the combination of a cylinder having a bore and a counterbore, a pair of concentric reciprocating valve sleeves within said bore, the outer of said sleeves having a collar thereon in lapped relation to said counterbore, means forming a passageway on said outer sleeve communicating with said counterbore, said

outer sleeve having an opening therethrough forming an outlet from said counterbore, and said inner sleeve acting as a valve to open and close said outlet.

5 6. In an internal combustion engine, the combination of a cylinder having a bore and a counterbore, a pair of concentric reciprocating valve sleeves within said cylinder bore, the outer of said sleeves having a collar thereon in lapped relation to the walls of said counterbore, means forming a passageway on said outer sleeve communicating with said counterbore, an opening in the wall of said outer sleeve above said collar for permitting fluids from 10 between said sleeves to enter said passageway, a second opening adjacent said collar forming an outlet for said counterbore, and valving means for said outlet.

15 7. In an internal combustion engine, the combination of a cylinder having a bore and a counterbore, a concentric sleeve within said bore having a collar thereon in lapped relation to the walls of said counterbore, said sleeve having ports above said collar, means forming a passageway on said sleeve communicating with said counterbore, said passageway extending upwardly toward said ports, means forming a second passageway communicating with said first passageway, 20 said second passageway extending circumferentially of said sleeve beneath said ports, and said counterbore having a valved outlet therefor.

25 8. In an internal combustion engine, the combination of a cylinder having a bore and a counterbore, a pair of concentric valve sleeves within said bore, the outer of said sleeves having a collar thereon in lapped relation to the walls of said counterbore, said outer sleeve having ports above said collar, means forming a passageway on said sleeve communicating with said counterbore, means forming a second passageway communicating with said first passageway, 30 said second passageway extending circumferentially of said sleeve beneath said ports, and said counterbore having an opening therethrough forming an outlet for said counterbore, and the inner of said sleeves acting as a valve to open and close 45 said outlet.

50 9. In an internal combustion engine, the combination of a cylinder having a bore and a counterbore, a pair of concentric valve sleeves within said bore, the outer of said sleeves having a collar thereon in lapped relation to the walls of said counterbore, means forming a passageway on said outer sleeve communicating with said counterbore, said outer sleeve having an opening therein forming an outlet from said counterbore and the inner of said sleeves having an opening therein adapted to register with said outer sleeve opening during the upstroke of said outer sleeve.

55 10. In an internal combustion engine, the

combination of a cylinder having a bore and a counterbore, a pair of concentric valve sleeves within said bore, the outer of said sleeves having a collar thereon in lapped relation to the walls of said counterbore, means forming a passageway on said outer sleeve communicating with said counterbore, the inner of said sleeves having an opening therein adapted to register with said outer sleeve opening during the upstroke of said outer sleeve, a reciprocating piston having a head within said inner sleeve covering said inner sleeve opening during a portion of its stroke, and an opening in said piston below said head for preventing said piston from obstructing said inner sleeve opening.

70 11. In an internal combustion engine, the combination of a cylinder having a recess therein, a reciprocating valve sleeve within said cylinder having an enlarged portion in lapped relation to said recess for forming a fluid pump, said pump having an outlet passage and a constantly open inlet passage and valving means for closing said outlet passage during the suction stroke of the 75 pump.

80 12. In an internal combustion engine, the combination of a cylinder having a recess therein, a pair of concentric reciprocating valve sleeves within said cylinder, the outer of said sleeves having an enlarged portion in lapped relation to the walls of said recess for forming a fluid pump, said outer sleeve having means forming a passageway thereon in constant communication with said pump for forming an inlet thereto, said outer sleeve having an opening therein forming an outlet from said pump, and said inner sleeve acting as a valve to close the outlet during the suction stroke of the pump.

85 13. A valve sleeve for an internal combustion engine, comprising a cylindrical portion, a portion projecting beyond the cylindrical portion adapted to act as a pump piston, and means forming a passageway on 90 the surface of said sleeve adapted to form a pump inlet.

95 14. A valve sleeve for an internal combustion engine, comprising a cylindrical portion, a portion projecting beyond the cylindrical portion adapted to act as a pump piston, means forming a passageway on the surface of said sleeve adapted to form a pump inlet, and an opening in said sleeve adapted to form a pump outlet.

100 15. A sleeve valve for internal combustion engine cylinders comprising a cylindrical member of uniform diameter and an enlarged portion unitary with the cylindrical member, adapted to be disposed within the 105 cylinder, said cylindrical portion having an aperture adjacent the enlarged portion.

115 16. A sleeve valve for internal combustion engines comprising a cylindrical portion of uniform diameter having a channeled outer 120

surface and an aperture for maintaining communication with the inner surface, and said sleeve being provided with an enlarged portion unitary with the cylindrical portion adapted to slidably engage the cylinder, said cylindrical portion having a second aperture therein adjacent the enlarged portion, communicatively associated with the first mentioned aperture.

10 In testimony whereof, I affix my signature.
